UNITED STATES PATENT OFFICE

CHARLES A. DREISBACH, OF NEW HAVEN, CONNECTICUT, ASSIGNOR TO STANDARD RADIAL BLAST CORPORATION, OF NEW YORK, N. Y., A CORPORATION OF NEW YORK

SCOURING CHAMBER FOR METAL-SCOURING MACHINES

Application filed March 25, 1929. Serial No. 349,701.

This invention relates to an improvement interposed between their opposite side-edges, in scouring-chambers and particularly to scouring-chambers for metal-scouring and similar machines designed for scouring the 5 surfaces of metal strips, sheets, and wire which are fed longitudinally through the scouring-chamber thereof.

The object of this invention is to provide a simple and effective scouring-chamber of the 10 type referred to and constructed with particular reference to insuring the repeated impact of the sand or other abrasive material against the metal to be scoured.

With the above object in view, my invention 15 consists in a scouring-chamber characterized by its provision with a plurality of inclined abrasive-deflecting surfaces arranged to deflect the sand or other abrasive material blown therethrough against the surface of the work.

20 My invention further consists in a scouring-chamber characterized as above and having certain details of construction and combinations of parts as will be hereinafter described and particularly recited in the claims.

25 In the accompanying drawings:

Fig. 1 is a view in side elevation showing my improved scouring-chamber installed in a metal-scouring machine which is broken away and shown partly in section;

30 Fig. 2 is a top or plan view thereof;

Fig. 3 is a broken enlarged-scale longitudinal sectional view taken on the line 3—3 of Fig. 2;

Fig. 4 is an enlarged-scale transverse sectional view taken on the line 4—4 of Fig. 1;

Fig. 5 is a detached perspective view of one of the two corresponding scouring-chamber plates which make up the scouring-chamber.

40 In carrying out my invention I employ two corresponding reversely-turned scouring-chamber plates 10 and 11, the inner face of each of which is of undulating form to provide inclined abrasive-deflecting surfaces 12 which act to deflect sand or other abrasive material toward the complementary plate and hence toward the respective opposite surfaces of a metal strip 13 which is drawn longitudinally through a scouring-passage 14 formed between the upper and lower plates 10 and 11 by spacing them apart by means of gaskets 15

as clearly shown in Fig. 4 of the drawings. The lower scouring-chamber plate 11 rests upon a plurality of transverse-bars 16, each of which is supported at its respective opposite ends in tie-bars 17 located upon the respective opposite sides of the scouring-chamber plates and secured by bolts 18 to the sand-supply chamber 19 and the oppositely-located sand-receiving chamber 20. In line with the opposite ends of the supporting-bars 16, each of the tie-bars 17 have secured to them up-standing brackets 21 having knuckle-like upper terminals 22 receiving the ends of transverse clamping-bars 23, one of which is located directly over each of the supporting-bars 16 aforesaid and secured at its opposite ends to the knuckles 22 of the aligned pair of brackets 21 by means of pins 24.

Extending downward through the clamping-bars 23 near each of the respective opposite ends thereof and in line with bosses 25 upon the upper scouring-chamber plate 10 is a clamping-screw 26 which acts to force the said upper scouring-chamber plate toward its 70 complementary lower plate 11 and thus compress the gaskets 15 therebetween and effectively prevent the escape of abrasive material. By removing one of the pins 24 the clamping-bar 23 may be swung upward and outward 80 upon the opposite pin so as to permit the ready removal of the said scouring-chamber plates 10 and 11.

The inlet end of the scouring-passage 14 formed between the inner faces of the upper 85 and lower scouring-chamber plates 10 and 11, registers with an opening 27 in a rectangular gasket 28, against which the adjacent ends of the said plates 10 and 11 abut. The said gasket also bears against the forward face of an inlet-head comprising two corresponding head-castings 29—29, each of which is grooved to form between them an inlet-passage 30 registering with the opening 27 in the gasket 28 95 and with the scouring-passage 14 aforesaid. Each of the head-castings 29 just described is provided with a flange 31 bearing against the forward face of a rectangular gasket 32 interposed between the same and the for- 100

ward face 33 of the sand-supply chamber 19 before described.

The outlet end of the scouring-passage 14 registers with an opening 34 in a rectangular gasket 35 which is pinched between the adjacent ends of the plates 10 and 11 and the inner face of an outlet-head comprising two corresponding complementary head-castings 36—36, each of which is grooved and placed together to form an outlet-passage 37 registering with the opening 34 in the said gasket and with the scouring-passage 14 aforesaid and leading into the sand-receiving chamber 20.

The rear face of the head composed of the complementary head-castings 36—36 is slightly curved from top to bottom, as clearly shown in Figs. 1 and 3, and is forced rearward toward the scouring-plates 10 and 11 by a pair of vertically-arranged clamping-bars 38—38 respectively located near the opposite side edges of the said head and bearing at their lower ends in bosses 39 and perforated at their upper ends for the reception of bolts 40 extending therethrough and through the forward wall of the sand-receiving chamber 20.

By tightening the bolts 40 just above referred to, rearward pressure is exerted upon the head-castings 36—36 so as to tightly grip the gasket 35 and compress the gasket 28 at the opposite ends of the said plates, which in turn will press the flanges 31 of the inlet head-castings 29—29 against the gasket 32, so as to maintain an airtight seal between the sand-supply chamber 19 and the outlet-passage 37 in the outlet head-castings 36—36.

The strip steel 13 or other work to be scoured is drawn endwise through the scouring-passage 14 by any suitable means in the direction of the Arrow A (Fig. 3) by any approved means, while a blast of air and sand is forced through the said passage preferably in the same direction and by a mechanism not requiring description herein, since it is well understood in the art. As the sand is forcibly driven through the said scouring-passage 14 it will be repeatedly deflected back and forth toward the work by the deflecting-surfaces 12 formed upon the respective inner faces of the plates 10 and 11, with the result that the work is thoroughly scoured and cleaned of scale or other coating by a single passage through the said chamber.

I claim:

1. A scouring-chamber for metal-scouring machines, having a scouring-passage of undulating longitudinal form, whereby a granular abrasive blown through the said passage will be repeatedly deflected against work therein.

2. A scouring-chamber for metal-scouring machines, having a scouring-passage, the walls of which are formed with abrasive-deflecting surfaces inclined with respect to

its longitudinal axis, whereby a granular abrasive blown through the said passage will be repeatedly deflected against work therein.

3. A scouring-chamber for metal-scouring machines, composed of two complementary plates positioned face to face to form a scouring-passage between them, the opposed faces of the said plates being formed with abrasive-deflecting surfaces inclined with respect to the longitudinal axis of the said passage. 70

4. A scouring-chamber for metal-scouring machines, composed of two complementary plates positioned face to face and spaced apart by a spacing-gasket to form a scouring-passage between them, the opposed faces of the said plates being formed with abrasive-deflecting surfaces inclined with respect to the longitudinal axis of the said passage. 80

5. A scouring-chamber for metal-scouring machines, composed of two complementary plates positioned face to face and spaced apart by a spacing-gasket to form a scouring-passage between them, the opposed faces of the said plates being formed with abrasive-deflecting surfaces inclined with respect to the longitudinal axis of the said passage, and clamping-means engaging both of the said plates for drawing them together to grip the said gasket. 85

6. A scouring-chamber for metal-scouring machines, composed of two complementary plates positioned face to face to form a scouring-passage between them, the opposed faces of the said plates being formed with abrasive-deflecting surfaces inclined with respect to the longitudinal axis of the said passage, an inlet-fitting and an outlet-fitting respectively engaging the opposite ends of the said complementary plates; and means tending to force the said fittings toward each other to 100 grip the said plates therebetween. 95

7. A scouring-chamber for metal-scouring machines, composed of two complementary plates positioned face to face to form a scouring-passage between them, the opposed faces 110 of the said plates being formed with abrasive-deflecting surfaces inclined with respect to the longitudinal axis of the said passage, and an inlet-fitting and an outlet-fitting respectively engaging the opposite ends of the said plates and each composed of a pair of complementary members grooved on their abutting faces to form a sand-passage. 115

In testimony whereof, I have signed this specification.

CHARLES A. DREISBACH.
